CLAIM

The ornamental design for a “casing for an analog watch”, as shown and described.

DESCRIPTION

FIG. 1 is a perspective view of a “casing for an analog watch”;

FIG. 2 is a left-side elevational view thereof;

FIG. 3 is a top plan view thereof;

FIG. 4 is a right-side elevational view thereof;

FIG. 5 is an end elevational view thereof;

FIG. 6 is the other end elevational view thereof; and,

FIG. 7 is a bottom plan view thereof.

The broken-line showings of hands and numerals in FIGS. 1 and 3 are for environmental purposes only and forms no part of the claimed design.
